[57] CLAIM

The ornamental design for a digital electronic instrument
design, as shown.

DESCRIPTION

FIG. 1 is a perspective view of a first embodiment of a
digital electronic instrument showing our new design;
FIG. 2 is a front plan view thereof;
FIG. 3 is a right side elevational view thereof;
FIG. 4 is a rear plan view thereof;
FIG. 5 is a left side elevational view thereof;
FIG. 6 is a top elevational view thereof;
FIG. 7 is a bottom elevational view thereof,
FIG. 8 is a perspective view of a second embodiment of a
digital electronic instrument showing our new design;
FIG. 9 is a front plan view thereof;
FIG. 10 is a right side elevational view thereof;
FIG. 11 is a rear plan view thereof;
FIG. 12 is a left side elevational view thereof,
FIG. 13 is a top elevational view thereof; and,
FIG. 14 is a bottom elevational view thereof.
